UNITED STATES PATENT OFFICE.

HENRY J. HILL, OF JERSEY CITY, NEW JERSEY.

MAIL RECEIVING AND DELIVERING DEVICE.

Application filed May 6, 1928. Serial No. 107,001.

This invention relates to mail receiving and delivery appliances and devices for railway trains and has for its object to provide a novel and improved means for engaging and disengaging a mail bag or pouch supporting element whereby the exchange of mail between a moving train and a station may be effected.

One of the objects of my invention is to provide improvements in mail delivery and receiving devices in that class of apparatus as set forth in the United States patent granted to me on November 9, 1909, No. 939,688 wherein the delivery and receiving devices of the railway car may be moved to either side thereof to engage the mail bag or pouch either on the left or right hand side of the track.

A further object of my invention is to provide a novel and improved delivery and receiving apparatus for railway cars and stations wherein the interchange of mail bags and pouches may take place while the said car passes in either direction or on either side of the railway bed and without attention on the part of the employees of the car or station.

To enable others skilled in the art to more fully understand and appreciate my invention that they may embody the same in the various modifications of structure and relation of parts contemplated, drawings depicting a preferred form of the invention have been annexed hereto as illustrating one embodiment thereof and in which drawings

Fig. 1 is a plan, partly broken away showing the interior of a car body and the relation of a mail receiving and delivery station on one side of a railway bed.

Fig. 2 is a vertical section through the car body showing the position of the apparatus therein whereby it may be moved to either the right or left hand side of the car.

Fig. 3 is a side view showing the station delivery and receiving apparatus and the car delivery and receiving apparatus.

Fig. 4 is an enlarged partial view with parts broken away showing the trussed hooks and rings of the station and car delivery and receiving apparatus.

Fig. 5 is a plan of the apparatus as shown in Fig. 4.

Referring now to the drawings wherein

like reference characters designate corresponding parts throughout the several views, 55 5 designates the railway bed and 6 the open door of a conventional type of railway mail car 7. Within the car, there is provided top and bottom guide rails or tracks 8, 9, extending between the opposed side doors whereby 60 the receiving and delivery device and apparatus of the car may be moved to either the right or left hand side as indicated by Fig. 2 of the drawing.

A carriage 10 having top and bottom 65 inwardly projecting extensions 11, 12 is attached to suitable plates 13 carrying rollers 14 operable in the guide rails or tracks 8, 9 being limited however in its extreme outward movement by the longitudinally extending door guide or rail 15. The carriage 10 is pivoted to swing on the vertical pins 16 of the top and bottom plates 13 so that it may be swung or turned around while in the car and moved to the opposite door or from the full line to the dotted line position shown by Fig. 2. Clamping screws 16^a hold the carriage when thus set.

The guide rails 8, 9 and the door guides 15 may be of light channel iron rigidly secured to the body of the car. The carriage 10 has a plate 17 bolted thereto as at 18. The plate 17 is formed with opposed ears 19 supporting a series of pins 20 passing through the vertical portion 21 of an arm supporting 85 bracket, buffer springs 22 being held on the pins so that the bracket may have a certain degree of longitudinal movement to offset the shock of receiving a heavy weight being transferred or released therefrom. The ears 90 23 of the bracket pivotally carry a substantially triangular arm 24, the leg 25 of which is formed with a ring supporting member 26 having a channel 27 therein to receive a closed ring 28. An extension 29 is pivotally 95 connected as at 30 to the ring supporting member, said extension having a depending ear 31 to which a spring 32 is connected, the opposite end of the spring being attached to the leg 25. The spring 32 normally maintains the extension open, the inward movement thereof being limited by the wall of the recess 33 and a stop pin or lug 34 but due to the weight of the hooks 35 to which the closed mail bag rings and the mail bags 100 105 or pouches are suspended, the extension is

closed. It will also be noted that the extension is also provided with a channel 36 to receive the ring 28 above referred to.

Consequently when the ring 28 is engaged by the apparatus of the railway car, the release of the weight from the extension 29, will permit the mail bags or pouches carried by the hooks 35 to be easily removed from the supporting arm without shock or damage. In order to compensate for the air pressure of a swiftly moving train and its apparatus in the path of the heavy weight of mail bags, the supporting arm and the bracket are supported on the pins and have a slight resilient movement against the resistance of the springs 22.

Having described the top, triangular supporting arm as carried by the bracket of the railway car, it is not deemed necessary to repeat the entire description of the construction of the lower, triangular supporting arm 37 of the receiving station or platform except that the said arm is provided with collars 38, 39 whereby it may be fastened by screws 40 to the vertical post 41 of a standard 42. The said arm is also braced by a central rib 43.

The receiving station or platform 44 between the standards 42 is braced by the trusses 45 and between the vertical posts 41 a gate or lattice work 46 is positioned by suitable collars 47 whereby the mail bags or pouches when delivered will be prevented from swinging around the respective supporting post.

The plate 17 of the car apparatus also supports a receiving arm 48 below the delivery arm being pivotally mounted thereon in the same manner. The said arm may consist of a casting in which the top slopes downwardly and inwardly forming a V-shaped depression 49 in which the ring of the mail bag slides when engaged by hook of the receiving arm. The receiving arm is also braced or trussed by suitable ribs to strengthen the structure, the central portion of said arm having a flexible element such as a chain 50 attached thereto which acts as a fulcrum.

Pivoted at 50° to the outer end of the receiving arm, I provide an elongated hook 51, having an inclined upper surface with notches 52 thereon to prevent the ring from slipping therefrom when it is disengaged from the delivery mechanism or apparatus of the car. The elongated hook 51 is connected to the receiving arm by links 52, 53 pivoted as at 54, said link 53 being in turn attached to the end of a sliding bar 55 of a guide 56. The sliding bar and links maintain the elongated hook 51 in its position and at all times parallel to the road bed whereby it may enter the ring 28, by means of a spring 57, said spring being connected to one end of the sliding bar and fastened at

its opposite end to the receiving arm. The tension on the spring draws the sliding bar inwardly so that the connected links are in their extended or aligned position as shown by Fig. 5 of the drawing.

The receiving arm and its elongated hook located at the top of the posts 41 of the platform or receiving station is similar in construction to the lower receiving arm of the car apparatus and consequently it will not be necessary to describe it in its entirety except that it is also provided with top and bottom collars 38, 39 whereby it may be secured to the post 41. It will be understood that the position of the delivery arm and receiving arm of the car apparatus and the station platform are just reversed, that is to say, the delivery arm of the car apparatus being at the top cooperates with the top receiving arm of the station platform, and the receiving arm at the bottom of the car apparatus cooperates with the bottom delivery arm of the station platform.

From the above description, the operation of the mechanism will be readily understood. Assuming that the carriage 10 has been moved to its extreme outer position the delivery and receiving arms will extend beyond the sides of the car and in the path of the receiving and delivery arms of a station platform as shown by Fig. 1. Since the diameter of the closed ring 28 is greater than the height of the receiving arm, the latter will pass through the ring and the moment the weight is released from the extension 29, the spring 32 draws it open permitting the ring to easily slide up on the hook 51 and down the sloping top to the dotted line position as shown by Fig. 4. At substantially the same time, the car apparatus receiving arm 105 may pass through the ring on the delivery arm of the platform or station whereby the mail bag or pouch or a plurality of bags or pouches may be transferred to the said car apparatus. Since the delivery and receiving arms of the car apparatus are above each other, each co-operating with the receiving and delivery arms of the station or platform, no interference results so that the transfer or interchange of the mail bags or pouches may take place at substantially the same moment.

Having shown and described my invention, I now claim as new:

1. A device of the class described comprising a carriage having inwardly projecting extensions, guide rails for said carriage whereby it may be moved to either side of a railway car, a plate secured to the carriage, a triangular arm hingedly connected to said plate, shock resisting means for said arm, a hook pivotally connected to the outer end of said arm and interconnected links between said arm and said hook.

2. A device of the class described comprising

ing a carriage, guide rails whereby said carriage may be moved to either side of a railway car, a plate secured to the carriage, a receiving arm pivotally connected to said carriage, said receiving arm consisting of a casting having a V-shaped depression for receiving a mail bag ring, a notched hook

pivots connected to the outer end of said casting and interconnected links between 10 said arm and said hook.

In testimony whereof I have affixed my signature.

HENRY J. HILL.
